US00D503439S

(12) **United States Design Patent** (10) Patent No.: **US D503,439 S**
(45) Date of Patent: **** Mar. 29, 2005**

(54) **RADIO FREQUENCY TOY CONTROLLER**

(75) Inventor: **Douglas M. Galletti**, Allen, TX (US)

(73) Assignee: **RadioShack Corporation**, Fort Worth, TX (US)

(**) Term: **14 Years**

(21) Appl. No.: **29/191,453**

(22) Filed: **Oct. 8, 2003**

(51) LOC (7) Cl. **21-01**

(52) U.S. Cl. **D21/566**

(57) **CLAIM**

The design for the radio frequency toy controller, as shown and described.

DESCRIPTION

FIG. 1 is a perspective view of the radio frequency toy controller showing my new design;

FIG. 2 is a front view thereof;

FIG. 3 is a side view thereof;

FIG. 4 is a side view thereof;

FIG. 5 is a rear view thereof;

FIG. 6 is a top view thereof;

FIG. 7 is a bottom view thereof; and,

FIG. 8 is a perspective view thereof.

Any broken line illustration of environmental structure in the drawings is not part of the design sought to be patented.
